CLAIM

The ornamental design for a suction cup apparatus holder, as shown and described.

DESCRIPTION

FIG. 1 is a perspective view of a suction cup apparatus holder; FIG. 2 is a right side view of the suction cup apparatus holder shown in FIG. 1,

FIG. 3 is a top view of the suction cup apparatus holder shown in FIG. 2,

FIG. 4 is a left end view of the suction cup apparatus holder shown in FIG. 2,

FIG. 5 is a right end view of the suction cup apparatus holder shown in FIG. 2,

FIG. 6 is a bottom view of the suction cup apparatus holder shown in FIG. 2; and,

FIG. 7 is a rear side view of the suction cup apparatus holder shown in FIG. 2.

The suction cup apparatus holder is used for supporting an apparatus holder on flat smooth surface for holding an adapter engaging an apparatus such as a cellular phone or a GPS for example, or an apparatus directly if it is designed to be directly engaged by the retaining structure on the apparatus holders support surface.
